DESIGN FOR A MACHINE FOR PEENING AND RESHAPING PISTONS

Van F. Lippard, Washington, D. C.

Application October 6, 1941, Serial No. 103,662

Term of patent 7 years

To all whom it may concern:

Be it known that I, Van F. Lippard, a citizen of the United States, residing at Washington, District of Columbia, have invented a new, original, and ornamental Design for Machines for Peening and Reshaping Pistons, of which the following is a specification, reference being had to the accompanying drawing, forming part thereof.

Figure 1 is a left side elevational view of a

machine for peening and reshaping pistons showing my new design; Fig. 2 is a front elevational view of the same; Fig. 3 is a right side elevational view of the same; and Fig. 4 is a rear elevational view of said machine showing my new design.

I claim:

The ornamental design for a machine for peening and reshaping pistons, as shown.

VAN F. LIPPARD.
